United States Patent Office.

WILLIAM R. CLARK, OF NORTH ADAMS, MASSACHUSETTS.

Letters Patent No. 90,996, dated June 8, 1869.

IMPROVEMENT IN LET-OFF MECHANISM FOR LOOMS.

The Schedule referred to in these Letters Patent and making part of the same.

To all whom it may concern:

Be it known that I, WILLIAM R. CLARK, of North Adams, in the county of Berkshire, and State of Massachusetts, have invented a new and improved Let-Off Mechanism; and I do hereby declare that the following is a full, clear, and exact description thereof, which will enable others skilled in the art to make and use the same, reference being had to the accompanying drawings, forming part of this specification.

This invention relates to improvements in let-off apparatus for looms, designed to provide a simple and efficient means for regulating the tension of the yarn, capable of ready adjustment for yarns varying in size.

The invention consists in an arrangement of worm-gearing and bell-crank levers, for varying the pressure of friction-straps on the beam-heads, as hereinafter more fully specified.

Figure 1 represents an elevation of a loom-frame, showing the yarn-beam, and

Figure 2 represents a transverse sectional elevation of the same, taken on the line *x x*.

Similar letters of reference indicate corresponding parts.

A represents bell-cranks pivoted to the loom-frame at *B*, and provided with adjustable slides *C*, upon their horizontal arms, bearing upon the upper edges of the friction-strap levers, *D*.

The other arms of these bell-cranks form toothed segments capable of gearing with the worm-gears *E*, upon the shaft *F*, pitched in opposite directions.

The shaft *F* derives motion, through other worm-

gears, *C*, from a shaft, *H*, driven from the yarn-beam by bevel-gears.

As the yarn is drawn from the beam, and the diameter of the roll gradually reduced, the motion imparted by the gearing to the segmental bell-cranks will gradually raise the horizontal arms thereof, reducing the pressure on the levers *D*, and thereby the friction on the drums of the beams.

The slides *C* are made adjustable on the bell-cranks, to or from the centre of motion thereof, to graduate the friction to yarns of different sizes, or numbers, and the horizontal parts of the said bell-cranks may be marked with numbers indicating the predetermined position of the slides for yarn of corresponding numbers.

For the larger sizes of yarns, the slides should be nearer the outer ends of the said horizontal parts of the bell-cranks.

One or more bell-cranks and friction-straps may be employed, as preferred.

Having thus described my invention, I claim as new, and desire to secure by Letters Patent—

The combination, with the levers *D* and friction-straps, of the bell-cranks having adjustable slides, and operated substantially as specified.

W. R. CLARK.
